PORTABLE FILING, MILLING, AND GRINDING MACHINE

Karel Patzak, Prague, Czechoslovakia

Application December 18, 1947, Serial No. 792,534
In Czechoslovakia September 9, 1946Section 1, Public Law 690, August 8, 1946
Patent expires September 9, 1966

6 Claims. (Cl. 74—16)

1

The present invention relates to a portable filing, milling and grinding machine with continuous revolution control and with two transmission gears for attaining the highest possible revolutions required for grinding by means of even the smallest grinding discs. This machine is serving mainly for finishing the machined moulds and dies and its speeds are to fulfill all the requirements of either the use of rotary files and milling cutters requiring smaller cutting speeds or of grinding discs requiring a higher circumferential speed or of even the smallest discs requiring top speeds. The machine according to the present invention allows of speeds within the range of between 1000 and 48,000 revs. p. min. and its outstanding feature is the continuous variability of said revolutions enabling the utilization of all rotary tools in a most rational manner.

The hitherto known machines of this type present a number of drawbacks. Their range of revolutions is comparatively small and does not at all suit the requirements of machining and finishing various materials. A stepwise variability of revolutions is prejudicious for the use of all sizes of rotary tools. In some cases the transmissions involve gearwheels always subjected to rapid wear and causing noisy running. Moreover, all familiar designs of machines of this type are unshielded.

According to the present invention all the above mentioned drawbacks will be eliminated by providing between the driving shaft and the first working shaft a transmission with continuous control, the most advantageous adjustment of the working revolutions of the machine being achieved in function of the indications of a scale including the kinds of materials under treatment and the respective diameters of the rotary machining tools. Consequently, the worker having in front of him the material to be worked, has only to read off on the scale the necessary tool diameter for carrying out the finishing operation and by placing the indicator on the respective division of the scale adjusts automatically the machine to the most advantageous revolutions owing to the arrangement of a continuous control between the driving shaft and the first working shaft.

The accompanying drawing illustrates, merely by way of example, an embodiment of the machine according to the present invention.

Fig. 1 showing a perspective view of the general arrangement of the machine,

Fig. 2 showing a front view of the machine

turned by 90° and a cross section on the line I—I in Fig. 1.

Fig. 3 showing a longitudinal section on line II—II in Fig. 2.

The portable filing, milling and grinding machine according to the invention comprises three flexible shafts, at the ends of which the respective rotary tools are being attached. The first flexible shaft, the so-called filing shaft 11a, is attached to the shaft 11 of the machine, a second flexible shaft, the grinding shaft 17a, is connected to the shaft 17 of the machine and a third shaft, the high-speed flexible shaft 20a, is connected to the shaft 20 of the machine.

The problem of continuous revolution control is solved by the provision of a friction transmission gear between the driving shaft of the electric motor of the machine and the first (the filing) working shaft turning within the lowest revolution range. This transmission is achieved by two bevel rollers 4 and 10. The drive roller 4 is directly connected to the shaft 3 of the electric motor 2 mounted in the machine. The transmission of the rotary force is performed through a slide wheel 6 coated with a rubber ring 5. Said wheel is freely supported on a moveable screw nut 7 threaded on the bolt 8 and secured against rotation by a projecting wire 30 or the like. By turning the wheel 9 which is fixed at the end of said screw 8 the frictional wheel 6 is displaced slidably through said nut 7 thus changing in a continuous manner the revolutions of said shaft 11 with threading 13 whereon the flexible shaft of the filing tool is attached, the range of change being between 1000 and 8000 revs. per minute.

Further revolutions, i. e. up to 24,000 per minute for the so-called grinding flexible shaft attached to the threading of shaft 17, are attained through a transmission achieved by an endless flat fabric belt 14 from the pulley 12 unto the pulley 18. The flat belt is adequately stretched by a spiral spring 19.

In the same manner the further transmission for the high-speed flexible shaft 20a attached to the threading of said shaft 20 is designed. Said flexible shaft is provided for the smallest grinding discs from 5 mm. up to 20 mm. in dia. and turning at between 24,000 and 48,000 revs. p. min. Said high-speed shafts 17 and 20 are supported in needle-bearings, ball bearings or the like. All these transmission gears are noiseless and the entire construction is shielded throughout. The main portion of the machine is enclosed in a two-part casing 1, the transmission gears being shielded by the cover 15.

On said casing 1 a switch 21 is provided with the inlet cable 22. The whole machine may rest on either a low or a high stand (see Fig. 1) and is turnable.

Fig. 1 illustrates also the arrangement of a handy scale 24 with indicator 29 extending inside the casing up to said slideable nut 7 of said transmission friction gear 6. Said scale includes all the types of material for the machining of which this machine is intended and in conformity with the properties of these materials, such as their strength, hardness etc. the required diameters of the respective rotary tools for machining said materials are calculated. These data are grouped in the individual lines of said table scale so that the worker by placing correspondingly the indicator may, without any necessity of calculating adjust through said wheel 9 the most advantageous revolutions, if he knows the material being machined and the diameter of the required rotary tool.

I claim:

1. A portable drive unit for driving shafts bearing tools for making an article, comprising in combination, a casing; an electric motor arranged in said casing and having a motor shaft arranged in said casing; a bevelled roller secured to said motor shaft; a first tool bearing shaft rotatably arranged in said casing parallel to said motor shaft; a bevelled roller secured to said first tool bearing shaft and having a slope being equal and opposite to the slope of said bevelled roller secured to said motor shaft so as to leave a space having a constant width between said bevelled rollers; a bolt supported by said casing in the central line of the space between said bevelled rollers; a slide wheel arranged on said bolt and engaging said bevelled rollers so as to transfer the rotation from said motor shaft to said first tool bearing shaft; means for shifting said slide wheel along said bolt so as to vary the gear ratio between said motor shaft and said first tool bearing shaft; a second tool bearing shaft rotatably arranged in said casing; and means arranged in said casing for driving said second tool bearing shaft by said first tool bearing shaft at a constant high speed ratio.

2. A portable drive unit for driving shafts bearing tools for making an article, comprising in combination, a casing; an electric motor arranged in said casing and having a motor shaft arranged in said casing; a bevelled roller secured to said motor shaft; a first tool bearing shaft rotatably arranged in said casing parallel to said motor shaft; a bevelled roller secured to said first tool bearing shaft and having a slope being equal and opposite to the slope of said bevelled roller secured to said motor shaft so as to leave a space having a constant width between said bevelled rollers; a bolt supported by said casing in the central line of the space between said bevelled rollers; a slide wheel arranged on said bolt and engaging said bevelled rollers so as to transfer the rotation from said motor shaft to said first tool bearing shaft; means for shifting said slide wheel along said bolt so as to vary the gear ratio between said motor shaft and said first tool bearing shaft; a second tool bearing shaft rotatably arranged in said casing; means arranged in said casing for driving said second tool bearing shaft by said first tool bearing shaft at a constant high speed ratio; a third tool bearing shaft rotatably arranged in said casing; and means arranged in said casing for driving said

third tool bearing shaft by said second tool bearing shaft at a constant high speed ratio.

3. A portable drive unit for driving shafts bearing tools for making an article, comprising in combination, a casing; an electric motor arranged in said casing and having a motor shaft arranged in said casing; a bevelled roller secured to said motor shaft; a first tool bearing shaft rotatably arranged in said casing parallel to said motor shaft; a bevelled roller secured to said first tool bearing shaft and having a slope being equal and opposite to the slope of said bevelled roller secured to said motor shaft so as to leave a space having a constant width between said bevelled rollers; a bolt supported by said casing in the central line of the space between said bevelled rollers; a screw nut arranged on said bolt; means for preventing said screw nut from rotating with respect to said casing and allowing said screw nut to rotate with respect to said bolt; a slide wheel rotatably arranged on the perimeter of said screw nut and engaging said bevelled rollers so as to transfer the rotation from said motor shaft to said first tool bearing shaft; means for shifting said slide wheel along said bolt so as to vary the gear ratio between said motor shaft and said first tool bearing shaft; a second tool bearing shaft rotatably arranged in said casing; and means arranged in said casing for driving said second tool bearing shaft by said first tool bearing shaft at a constant high speed ratio.

4. A portable drive unit for driving shafts bearing tools for making an article, comprising in combination, a casing; an electric motor arranged in said casing and having a motor shaft arranged in said casing; a bevelled roller secured to said motor shaft; a first tool bearing shaft rotatably arranged in said casing parallel to said motor shaft; a bevelled roller secured to said first tool bearing shaft and having a slope being equal and opposite to the slope of said bevelled roller secured to said motor shaft so as to leave a space having a constant width between said bevelled rollers; a bolt supported by said casing in the central line of the space between said bevelled rollers; a screw nut arranged on said bolt; means for preventing said screw nut from rotating with respect to said casing and allowing said screw nut to rotate with respect to said bolt; a slide wheel rotatably arranged on the perimeter of said screw nut and engaging said bevelled rollers so as to transfer the rotation from said motor shaft to said first tool bearing shaft; means for shifting said slide wheel along said bolt so as to vary the gear ratio between said motor shaft and said first tool bearing shaft; a second tool bearing shaft rotatably arranged in said casing; and means arranged in said casing for driving said second tool bearing shaft by said first tool bearing shaft at a constant high speed ratio.

5. A portable drive unit for driving shafts bearing tools for making an article, comprising in combination, a casing; an electric motor arranged in said casing and having a motor shaft arranged in said casing; a bevelled roller secured to said motor shaft; a first tool bearing shaft rotatably arranged in said casing parallel to said motor shaft; a bevelled roller secured to said first tool bearing shaft and having a slope being equal and opposite to the slope of said bevelled roller secured to said motor shaft so as to leave a space having a constant width between said bevelled rollers; a bolt supported by said casing in the

central line of the space between said bevelled rollers; a screw nut arranged on said bolt; means for preventing said screw nut from rotating with respect to said casing and allowing said screw nut to rotate with respect to said bolt; a slide wheel rotatably arranged on the perimeter of said screw nut and engaging said bevelled rollers so as to transfer the rotation from said motor shaft to said first tool bearing shaft; means for rotating said bolt with respect to said casing so as to shift said slide wheel along said bolt so as to vary the gear ratio between said motor shaft and said first tool bearing shaft; an indicator rigidly connected to said screw nut and having an extension; a scale plate arranged outside said casing for cooperation with said extension of said indicator so as to permit an adjustment of said screw nut with respect to said bolt thereby adjusting the gear ratio between said motor shaft and said first tool bearing shaft; a second tool bearing shaft rotatably arranged in said casing; and means arranged in said casing for driving said second tool bearing shaft by said first tool bearing shaft at a constant high speed ratio.

6. A portable drive unit for driving shafts bearing tools for making an article, comprising in combination, a casing; an electric motor arranged in said casing and having a motor shaft arranged in said casing; a bevelled roller secured to said motor shaft; a first tool bearing shaft rotatably arranged in said casing parallel to said motor shaft; a bevelled roller secured to said first tool bearing shaft and having a slope being equal and opposite to the slope of said bevelled roller secured to said motor shaft so as to leave a space having a constant width between said bevelled rollers; a bolt supported by said casing in the central line of the space between said bevelled rollers; a screw nut arranged on said bolt; means for preventing said screw nut from rotating with

respect to said casing and allowing said screw nut to rotate with respect to said bolt; a slide wheel rotatably arranged on the perimeter of said screw nut and engaging said bevelled rollers so as to transfer the rotation from said motor shaft to said first tool bearing shaft; means for rotating said bolt with respect to said casing so as to shift said slide wheel along said bolt so as to vary the gear ratio between said motor shaft and said first tool bearing shaft; an indicator rigidly connected to said screw nut and having an extension; a scale plate arranged outside said casing for cooperation with said extension of said indicator so as to permit an adjustment of said screw nut with respect to said bolt thereby adjusting the gear ratio between said motor shaft and said first tool bearing shaft; a second tool bearing shaft rotatably arranged in said casing; means arranged in said casing for driving said second tool bearing shaft by said first tool bearing shaft at a constant high speed ratio; a third tool bearing shaft rotatably arranged in said casing; and means arranged in said casing for driving said third tool bearing shaft by said second tool bearing shaft at a constant high speed ratio.
